CECIL S. KELLEY, OF EAST MCKEESPORT, PENNSYLVANIA, ASSIGNOR TO THE WEST INGHOUSE AIR BRAKE COMPANY, OF WILMERDING, PENNSYLVANIA, A CORPORATION OF PENNSYLVANIA

METAL DIAPHRAGM

Application filed April 20, 1927. Serial No. 185,346.

The invention relates to flexible diaphragms of the type adapted to be clamped at its outer edge and which is flexed in service to accomplish various purposes.

The principal object of my invention is to provide a flexible metallic diaphragm, which for a given thickness of material, will have greater strength, will deflect under load, a greater distance, a greater number of times, than has hitherto been possible without damage to the diaphragm.

Another object of the invention is to provide a flexible metallic diaphragm in which the metal is so disposed, that when the diaphragm is subjected to the action of loads, the stresses set up therein will be distributed in different directions over the flexing portion of the diaphragm and will thus reduce to a minimum the liability of damage to the diaphragm, due to repeated flexing.

A further object of the invention is to provide a metallic diaphragm having increased sensitivity.

These and other objects and advantages will be apparent from the following detailed description.

Referring to the drawing, in which like reference characters refer to like parts, Fig. 1 is a face view of a metallic diaphragm formed in accordance with the invention, several of the corrugations being shown in detail; Fig. 2 is a sectional view of the same taken on the line 2—2 of Fig. 1; and Fig. 3 is an enlarged cross-sectional view taken on the line 3—3 of Fig. 2.

As shown in the accompanying drawing, the flexible diaphragm is preferably made from thin metal and may comprise an outer flat annular clamping flange 1, a central flat circular follower portion 2 and an intermediate annular trough-shaped portion 3, all of which are preferably integral. In Fig. 2 of the drawing the flange 1 and the circular follower portion 2 have been shown as being in the same plane with each other, but it will be understood that they may be disposed in different planes.

The annular trough-shaped portion 3 is preferably of semicircular form in cross section and is provided with a plurality of

radially arranged semi-circular corrugations 4 which may be of any suitable form in cross section; but, as shown considerably enlarged in Fig. 3 of the drawing, are preferably formed with curved top and bottom walls 5 and 6 respectively, and flat wall portions 7. These corrugations are deepest at substantially the bottom of the portion 3, or in other words, on or about a line substantially midway between the inner edge of the clamping flange 1 and the outer edge of the follower portion 2 and preferably concentric with these edges. From their deepest portions the corrugations taper to their shallowest depth at their ends. The outer ends of the corrugations merge into a plain annular portion 8 which is adjacent the clamping flange 1, while the inner ends merge into a curved portion 9 connecting the circular follower portion 2. Besides tapering in depth, the corrugations also taper from their greatest width at their ends adjacent the portion 8, to their least width adjacent the follower portion 2.

When in operative position the clamping flange 1 is secured against movement and when the diaphragm is subjected to the action of loads in the direction as indicated by the arrow in Fig. 2 of the drawing, the portion 2 as a whole will be moved downwardly and the portion 3, due to the rigidity of the corrugations 4, will begin to flex at or adjacent the place where the corrugations merge into the annular portion 8, and as the movement is continued the corrugated portion will flex, causing the walls of the corrugations to flex transversely of the corrugations away from each other, that is to say, the corrugations will have a tendency to flatten, such tendency being greatest at the outer ends of the corrugations and gradually decreasing as the inner ends of the corrugations are approached. When the diaphragm is subjected to the action of loads in a direction opposite to that indicated by the arrow in Fig. 2, the walls of the corrugations will flex transversely of the corrugations toward each other. It will be noted that in a diaphragm formed in accordance with the invention, the metal is so disposed that, in operation, the liability of

breakage of the diaphragm, due to repeated flexing, is reduced to a minimum.

In the drawing, there has been shown, only one arrangement of the corrugations, but it will be seen that there may be other arrangements used without departing from the spirit and scope of the appended claims.

Having now described my invention, what I claim as new and desire to secure by Letters Patent, is:—

- 10 1. A flexible metallic diaphragm comprising an outer clamping flange, an inner follower portion and an intermediate trough-shaped portion having cylindrical portions adjacent said flange and follower portion, and corrugations formed in said trough-shaped portion and merging into said cylindrical portions.
- 15 2. A flexible metallic diaphragm comprising an outer clamping flange, an inner follower portion and an intermediate trough-shaped portion having cylindrical side portions extending at angles to said flange and follower portion, and a corrugation extending from one of said cylindrical portions to the other.
- 20 3. A flexible diaphragm having a trough-shaped portion and tapering corrugations extending in directions across said trough-shaped portion, said portion having cylindrical portions at the ends of said corrugations.
- 25 4. A flexible diaphragm having a trough-shaped portion and flexible corrugations extending in directions across said trough-shaped portion and terminating in cylindrical portions forming parts of said trough-shaped portion.
- 30 5. A flexible metallic diaphragm comprising an outer clamping flange, an inner follower portion and an intermediate trough-shaped portion having corrugations formed therein which taper in width and depth and merge into cylindrical portions forming parts of said trough-shaped portion.

In testimony whereof I have hereunto set my hand.

CECIL S. KELLEY.
